APPARATUS FOR TREATING PATIENTS BY
BODILY MOVEMENTS

Karol Mayer, Poznan, Poland

Application February 17, 1933, Serial No. 657,278
In Germany August 26, 1932

5 Claims. (Cl. 128—24)

The invention relates to an apparatus for treating patients by bodily movements, the curing effect of which is amplified by special movements in comparison to the well-known apparatus, on therapeutic beds, and the structure of which permits any desired adaption according to circumstances.

Oscillating beds are already well-known which are suspended on their axes in an oscillating and rotating manner and which can be rotated by mechanical driving devices; special boxes are also well-known fitted in the interior with elastic mattresses and provided with a lockable lid, openings being left free for the face and the limbs, for instance, the arms and hands, of the patient.

The object of the invention is to provide an apparatus of the type referred to, to which, in addition to its rotary movement, an oscillating movement is imparted and the drive of which is further connected with a regulating device. According to the invention, means are provided at the head and foot of the bed in order to insert shaft members—transferring the oscillation to the bed—at various points and in order to rotate the bed uniformly or intermittently so that the head and the foot of the bed are alternately lifted or lowered during the oscillation, in order to further facilitate the circulation of the blood of a human being or an animal lying in the bed, with the aid of gravity and, therefore, to facilitate the necessary blood shifting.

Holes provided at different heights in the walls of the therapeutic bed and serving for the reception of the shaft members, can each be replaced by a guiding slot (Figures 3 and 6) in the end walls of the therapeutic bed whereby the necessary withdrawal and insertion of the shaft members in changing the position of the level is unnecessary, this result being accomplished by sliding the shaft members in the guiding slots in the desired position and securing the shaft members in this position by suitable means.

It is well known that the hydrostatic pressure exercises a considerable influence on the circulation of the blood, an influence which is utilized in many cases for diagnostic and therapeutic purposes. But, the well-known medico-mechanical arrangements serving for the above mentioned purposes have various disadvantages, especially it is not possible to effect with them an uninterrupted changing and exactly regulated influence of gravity on different sections of circulation; the bed according to the invention, turn-

able at will in different directions proves to be far more essentially advantageous and simple.

In the drawings, some examples of the invention are diagrammatically shown:

Figure 1 is the side view of a turnable therapeutic bed in an inclined position during a phase of the eccentric rotation;

Figure 2 is a similar view of the same bed, but rotated further on, in a horizontal position;

Figure 3 is a side view of another construction of the therapeutic bed in connection with one of the well-known driving mechanisms for the therapeutic bed;

Fig. 4 is a side view of the gear mechanism with a portion of the casing broken away;

Fig. 5 is a cross section on the line 5—5 of Fig. 3;

Figure 6 is an end view showing the elliptical shape of the therapeutic bed according to Figure 3 with the guides for the shaft members.

In Figures 1 and 2, the frames 2 of the bed are fitted with elastic springs 1, forming a lockable box upholstered on the inner side with mattresses so that during the rotation of the bed the body lies comfortably in every position on a soft base. The lid 3 is hinged at 3' and is provided with an opening 4 for the face and a second opening 5 for the hands, so that the person lying in the box can open the lid 3 and can move the hands in a convenient manner.

At 6, the locking device for the lid is shown. At 7, holes for the insertion of the shaft members 8 and 88 are represented which shaft members are supported by frames 9 and 9a and are set in a vibrating or uniformly rotating movement, or alternating rotation—for instance once to the left and once to the right—in the well-known manner by the aid of corresponding regulators and a noiseless motor 10. The rotation and the adjustment of the axis can be altered and adjusted for diagnostic and therapeutic purposes to a large extent with the aid of corresponding regulators interposed before or after the driving gear.

It is quite apparent that by withdrawing the shaft members 8 and 88 from the openings in which they are placed and inserting them in others of the openings 7 the position of the bed relative to the shaft members can be varied. Either one or both of the shaft members may be shifted, and a great number of different positions may thus be obtained. In this fashion various degrees and types of oscillatory movement of the bed can be obtained.

The position of the body of the person lying

in the box is changed by the above described simple device in a convenient and regulatable manner and, therefore, the influence of the gravity component on necessary blood shifting for diagnostic and therapeutic purposes, is possible in an advantageous manner. The further technical improvement of the present invention consists in the fact that the person during the treatment can sleep, read and even do some work as the hands are free.

The holes 7 provided at different heights in the end walls of the therapeutic bed and serving for the reception of the shaft members 8 and 88, can each be replaced by a guiding slot 16 (Figures 3 to 6) in the front and the back walls 15 of the therapeutic bed whereby the necessary withdrawal and insertion of the shaft members 8 and 88 in changing the position of the level is unnecessary, this result being accomplished by 20 sliding the shaft members 8 and 88 in the guiding slots 16 to the desired position and securing the shaft members 8 and 88 in this position by suitable means.

In order to obtain a steady movement of the therapeutic bed completely free from jerks, it is suitable to substitute for a part of the shaft members 8 and 88 transferring the movement to the therapeutic bed, a spring 13 which absorbs the jerks coming from the driving motor 10.

This spring consists of two flat portions connected by bowed elements 38, the flat portions being secured by bolts 39 to plates 36 and 37 which are mounted respectively on the shaft member 8 or driven shaft and a shaft section 35 the end of which carries a key member 16' which slides in the slot 16 on the end wall 15 of the bed.

The motor 10 drives the shaft member 8 through the gearing arrangement shown in Figs. 3 and 4. The motor shaft 18 carries a gear 19 which meshes constantly with a gear 20 on shaft 21. Slidably mounted on shaft 21 and controlled by a lever 14 having a handle 27 are two gears 22 and 23 of different size, formed on a single sleeve 24. These gears mesh respectively with gears 25 and 26 fixed on shaft member 8. By sliding the sleeve 24 through lever 14 which is pivoted at 28, gears 22 and 23 may be selectively brought into mesh with gears 25 and 26 thereby varying the speed to which shaft 8 is driven.

50 The speed of the motor may be regulated by a rheostat 17 or in some other suitable manner through control of the electric current.

The shaft 21 carries a further gear 29 which meshes with a gear 30 on shaft 31. An eccentric 31' mounted on shaft 31 through its strap 12 engaging ring 35' and eccentric rod 33 on shaft section 35 will impart vertical movement to the shaft 35 which is permitted by the flexibility of the spring connection 13.

60 The spring 13 amplifies the action of the springs 1 which form the support for the body of the person being treated. If such springs are used at both ends of the bed, then often the springs 1 can be omitted. Springs 13 will act to permit an additional swinging movement of the bed which is cushioned by their elasticity. The eccen-

tric 31' imparts an additional oscillating movement to the shaft section 35.

The gearing arrangement and the rheostat permit the operator to obtain almost any desirable speed of movement. In this way the movements can be arranged and varied to suit the particular case being treated.

The box 2 serving as a therapeutic bed is not bound to a rectangular shape in its section; it may be suitable in some cases, to give the box 10 2 an elliptical form (Fig. 6). By this means the box bed becomes as small and light as possible. As the elliptical form accommodates itself to the human body which has likewise essentially an elliptical cross section, unfilled places are avoided 15 and volume and weight of the box can be reduced to a minimum.

What I claim is:

1. In an apparatus for treating patients by bodily movements, a box for holding the patient, means to support said box to turn about a substantially horizontal axis, said means including a shaft, means for connecting said shaft to one end of the box, a motor, means to connect said motor to said shaft to turn the same, a second shaft driven by said motor, an eccentric mounted on said second shaft, and means connecting said eccentric to said first shaft to impart lateral movement to said first shaft.

2. In an apparatus for treating patients by bodily movements, a pair of substantially horizontal aligned shaft members, a spring device carried by one of said shaft members, a box for holding the patient secured at one end to the second shaft and at the other end to said spring device, means to adjust the points of connection of the shaft member having said spring device to said box, and motor driven means to impart a transverse movement to the end of the box which is connected to said spring device.

3. In an apparatus for treating patients by bodily movements, a divided shaft, a spring having a pair of parallel members one of which is connected to one, and the other is connected to the other part of said divided shaft, means for moving said shaft about its axis, a box for holding the patient, and means for operatively connecting said box to said shaft in various positions with respect to the axis of the shaft.

4. In an apparatus for treating patients by bodily movements, axially aligned and axially spaced shaft members, a box arranged between the inner ends of said shaft members, and an end plate at one of the outer ends of said box which end plate has a plurality of holes for the reception of the inner end of the corresponding shaft member.

5. In an apparatus for treating patients by bodily movements, axially aligned and axially spaced shaft members, a box arranged between the inner ends of said shaft members, and a slotted part for operatively connecting one of the outer ends of said box to the inner end of the corresponding shaft in various positions with respect to the axis of said shaft members.

KAROL MAYER.
